UNITED STATES PATENT OFFICE.

MAURICE J. WOHL, OF BROOKLYN, NEW YORK, ASSIGNOR TO M. J. WOHL & COMPANY, INC., A CORPORATION OF NEW YORK.

ARC-LAMP.

1,319,825.

Specification of Letters Patent.

Patented Oct. 28, 1919.

Application filed November 23, 1917. Serial No. 203,500.

To all whom it may concern:

Be it known that I, MAURICE J. WOHL, a citizen of the United States, and resident of Brooklyn, city of New York, county of 5 Kings, and State of New York, have invented certain new and useful Improvements in Arc-Lamps, of which the following is a specification.

This invention relates, generally, to electric arc lamps and more particularly, in 10 some features thereof, to multiple arc lamps in which a unitary mechanism is employed to control several arcs.

The invention has for a general object to 15 provide a unitary and self contained arc lamp in which the control mechanism is widely separated from and also heat-insulated from the arc or arcs.

The invention has for another object to 20 provide a multiple arc of this type lamp in which the different carbon pairs are located in separate compartments.

A further object is to provide an arc lamp in which the mechanism is separate 25 and heat-insulated from the arc or arcs.

Other objects relate to the construction of the arc lamp casing in special sections for provision of the separate chambers and also to the general arrangement of parts 30 looking to simplicity of construction and regular feed of the carbons.

For further comprehension of the invention, and of the objects and advantages thereof, reference will be had to the following description taken in connection with the accompanying drawings in which I have illustrated a preferred embodiment of the invention, the various novel features being more particularly pointed out in the appended claims.

Figure 1 of the drawings is a longitudinal vertical sectional view of an arc lamp embodying the invention, this view being taken on the line 1—1 of Fig. 2.

Fig. 2 is a horizontal sectional view taken on the line 2—2 of Fig. 1.

Fig. 3 is a transverse vertical section on the line 3—3 of Fig. 1.

Fig. 4 is a transverse vertical section on the line 4—4 of Fig. 1.

In the present embodiment of the invention the main frame of my improved arc lamp comprises an upper casting 1 and a lower casting 2, each of oblong form in 55 plan view. These castings are rigidly se-

cured together by a plurality of vertical posts arranged in two pairs numbered 3 and 4, respectively. These posts are spaced in pairs on opposite sides of the center line of the lamp, when considered in face view, 60 as will be apparent from Figs. 1 and 2, in any well known manner at their upper and lower ends.

Located centrally between the respective pairs of posts and adjacent the upper casting 65 1 is a solenoid 6, which may be secured to the upper casting in any suitable manner. In the present instance the solenoid is mounted between a pair of horizontal plates 7, 7' fixed to a pair of vertical rods 8, 8' whose 70 upper ends are rigidly secured to the casting 1. The lower ends of these rods extend downwardly below the solenoid and have attached thereto a shelf 9 upon which is mounted, co-axially with the solenoid 6, 75 a dash-pot 10 whose plunger 11 is connected to the core 12 of the solenoid 6.

I prefer to provide a resilient connection between the plunger 11 and core 12, this connection being here in the form of a 80 pair of vertically spaced and horizontally extending flat springs 13 and 14 connected, respectively, midway between their ends, to the upper end of the plunger 11 and the lower end of the core 12, and secured together at their ends as by the studs 15. It will be apparent that the solenoid and dash pot are mounted on a common subsidiary frame readily detachable from the main frame without disruption of the latter. 90

My improved lamp, as here embodied, comprises two pairs of carbons, or, broadly speaking, two arc forming devices. These arc forming devices are located on opposite sides of the solenoid 6 and are controlled 95 thereby and comprise upper carbons 20, 20' fixed in vertically adjustable sockets 21, 21' and lower carbons, 22, 22' fixed in stationary sockets 23, 23'. The lower sockets 23, 23' are here shown as mounted on the ends of fixed 100 lateral arms 24, 24' secured to and insulated from a plate 25 carried rigidly by the posts 3 and 4.

The upper sockets 21 and 21' are controlled by a clutch mechanism from the 105 solenoid. As here shown, crossheads 26, 26' are slidably mounted on the respective posts 3, 4 and have secured thereto the insulated lateral arms 28, 28', having the respective sockets 21, 21' on their ends. Fixed to each 110

of the crossheads and extending downwardly therefrom between the respective pairs of posts are rods 30, 30', which I term "dummy carbons," and which are adapted to be engaged by clutches and so control the carbons.

As here shown, a transverse bar 35 is fixed midway between its ends to the spring 13 and is connected at its ends to the upper ends of a pair of longitudinally resilient rods 10 whose lower ends are attached to clutches 37, 37', of any well known construction, which engage the dummy carbons. I have here shown these longitudinally resilient rods as comprising upper and lower rigid members 38, 38' and 39, 39' joined together by the angular springs 40, which are secured at opposite ends to the respective member 38, 38' and 39, 39', this type of resilient rod being fully described and illustrated in a previous patent issued to me July 31, 1917, under No. 1,235,271.

The resistances with which arc lamps are provided I have here shown at 44 as secured to and depending from a plate 45 carried by 25 the posts 3, 4, below the control mechanism just described. To provide for easy attachment and detachment of the resistances I have shown the plate 45 as provided with key-hole apertures 46 through which pass 30 the headed screws 47 which are threaded into the ends of the resistance spools.

As will be apparent from the above description, the arcs are widely separated from the control mechanism, and, to further insulate the latter from the heat of the arcs, I 35 provide heat insulating partitions which divide the arc lamp casing into the central compartment, containing the control mechanism, and side chambers, containing the 40 arcs.

In the present instance, I effect this by means of a channel-shaped partition member 50 which incloses the control mechanism on the front and sides of the latter and may be 45 secured, as by screws 51, to the plate 45. Each leg of this member 50 is cut away at its lower end, as at 52, to receive the adjacent fixed carbon supporting arm, and vertically slotted as at 53, for approximately the 50 upper half of its length, to accommodate the movable carbon supporting arm.

The main inclosing casing of the arc lamp is carried by the castings 1 and 2 and comprises a back portion 55 and side portions 55 56, this casing inclosing the arcs on back and sides of the lamp. The arcs, as will be apparent, are disposed in side chambers in this casing on either side of the compartment formed by the partition member 50 in which 60 the control mechanism is located.

The castings 1 and 2 are merely skeleton frames, as clearly shown, and the side compartments in which the arcs are located are thus open at top and bottom to assist in the 65 rapid carrying off of the heat from the arcs.

The ventilation of the central compartment containing the control mechanism may be assisted by perforating that section of the back 55 of the main casing within the confines of the partition 50, as indicated at 58. 70

The front of the casing may be provided with a flaring member 60 carrying in its forward end a slide 61 which may be employed to shut off the light from one of the arcs when desired. 75

The walls of the side chambers in which the arcs are located serve also as reflectors, as will be apparent, the invention being here embodied in an arc lamp designed more particularly for use in motion picture work or 80 for other illumination for photographic purposes.

I have not considered it necessary to illustrate the electrical connections, which may be through the solenoid down one pair of 85 carbons, through the resistances and up through the other pair of carbons, the insulated arms 24 and 28 forming the medium for connection to the carbons.

As a convenient way of detachably mounting 90 the lamps I have provided the castings 1 and 2 with vertically perforated legs 65 and 66 adapted to receive freely a post 67 projecting rigidly upwardly from a saddle 68 on the upper end of a standard 69, the 95 saddle being shaped to fit the bottom of the casting 2, which rests thereon.

As will be apparent, when the lamp is in operation, the clutches 37, 37' will engage the dummy carbons 30, 30' and the latter 100 will cause the cross heads 26, 26' through the arms 28 and 28' to regulate the arcs as the carbons burn away.

What I claim is:—

1. An arc lamp provided with an oblong 105 casing, a pair of arc forming devices located in said casing one near each end thereof, unitary control mechanism for said arc forming devices and located between the latter, and a channel-shaped partition member 110 inclosing said control mechanism with its legs extending toward the back of the casing.

2. An arc lamp provided with an oblong casing, a pair of arc forming devices located in said casing one near each end thereof, 115 unitary control mechanism for said arc forming devices and located between the latter, and a channel-shaped partition member inclosing said control mechanism with its legs extending toward the back of the casing, that portion of the back of the said casing within the confines of the said legs being perforated. 120

3. In an arc lamp, a pair of arc forming devices, unitary control mechanism therefor 125 located between said devices, and heat insulating partitions interposed between said arc forming devices and control mechanism.

4. An arc lamp provided with an oblong 130 casing divided longitudinally into a central

compartment and a plurality of side chambers, an arc forming device located in each of the side chambers, and a unitary control mechanism located in the central compartment for said arc forming devices.

5 5. An arc lamp provided with an oblong casing divided longitudinally into a central compartment and a plurality of side chambers open at the top and bottom to provide 10 for air circulation, an arc forming device located in each of the side chambers, and a unitary control mechanism located in the central compartment for said arc forming devices.

15 6. An arc lamp provided with an oblong casing divided by partitions into a central

compartment and a plurality of side chambers, a pair of carbons located in each of said side chambers, a unitary carbon control mechanism located in said central compartment, said mechanism including a plurality of dummy carbons and carbon-carrying arms projecting laterally from each of said dummy carbons into each of said side chambers, the said partitions being vertically 20 slotted to permit of vertical movement of said arms.

25 Signed at city of New York, county of Kings and State of New York, this 13th day of November, 1917.

MAURICE J. WOHL.
